UNITED STATES PATENT OFFICE.

DAVID B. HART, OF NEW YORK, N. Y.

TRUNK CONSTRUCTION.

1,398,016.

Specification of Letters Patent.

Patented Nov. 22, 1921.

Application filed November 4, 1920. Serial No. 421,664.

To all whom it may concern:

Be it known that I, DAVID B. HART, a citizen of the United States, and a resident of the city of New York, borough of Manhattan, in the county and State of New York, have invented a new and Improved Trunk Construction, of which the following is a full, clear, and exact description.

This invention relates to an improvement 10 in the construction of trunks and refers particularly to trunks of the sectional type especially designed for traveling salesmen.

At present it is the custom for a traveling salesman to resort to the use of a plurality 15 of trunks, the combined number serving to carry a full line of goods to be demonstrated, and one or more of said trunks being designed to carry a smaller line of goods. Under this practice, the separate trunks 20 frequently become separated and cause untold inconvenience and a loss of time.

It is therefore an object of the present invention to provide a trunk including a plurality of independent sections capable of being nested and locked to each other to overcome the above recited objection.

Another aim and object of the invention is to provide adjustable means for connecting and locking any number or all of the 30 sections together.

With the above recited and other objects in view, the invention resides in the novel construction, combination and arrangement of parts set forth in the following specification, the appended claims and the accompanying drawings, in which—

Figure 1 is a perspective view of a trunk constructed in accordance with the present invention and illustrating the several sections thereof secured in nested relation.

Fig. 2 is a longitudinal sectional view therethrough taken approximately on the line 2—2 of Fig. 4.

Fig. 3 is an end view thereof.

Fig. 4 is a transverse sectional view taken approximately on the line 4—4 of Fig. 2.

Fig. 5 is a detail fragmentary side elevation of the detachable joint between the securing band sections.

Fig. 6 is a perspective view of the same detached.

Referring to the drawings by characters of reference, the trunk comprises a plurality of sections 10, 11, and 12, said sections 55 being preferably of different heights. The sections are of identical construction and

each is provided at one side thereof with a cover 13 having an independent lock 14. The top of each trunk is provided with a central longitudinal groove 15 and at the bottom with a similar groove 16. The bottom of each trunk is further provided with longitudinally extending ribs 17 and the top of each of the trunk sections is provided with spaced, longitudinal grooves 18 disposed at opposite sides of the center groove 15 and parallel thereto. The grooves 18 are designed to receive the ribs 17 when the sections are arranged in associated relation. When the sections are detached the ribs 17 function in the usual manner as supporting runners upon which the trunk rests on a supporting surface. If desired the trunk sections may be partitioned or provided with sliding drawers 19 as illustrated, this arrangement being optional to the manufacturer. The means for securing and locking the trunk sections together comprises a band including the common top and bottom sections 20 and 21 and the side sections 22, 23 and 24. The sections 22, 23 and 24 correspond in length to the height of their respective trunk sections and each of said bands is provided at its upper end with a reduced neck 25 having laterally disposed 85 trunnions 26. The bottom terminal of each section is provided with spaced hooks 27 constituting knuckles adapted to respectively receive the trunnions 26, with the neck 25 disposed in the space therebetween. The 90 bottom section 21 is provided at both of its ends with reduced necks having trunnions 26. The top section 20 is provided at one extremity with the spaced hooks 27 and has hinged as at 28 to its opposite extremity 95 a lock hasp 29 provided with a lock section 30 which is designed to coöperate respectively with any one of the lock sections 31 carried respectively by the sections 22, 23, or 24, adjacent their upper ends.

In use of the trunk, any two or more of the trunk sections 10, 11, and 12 may be locked together by associating the respective band sections corresponding to the trunk sections. For instance, if it is desired to 105 associate the sections 10 and 11 only, the lock section 30 carried by the lock hasp 29 is released from the lock section 31 of the band section 24, and the hooks 27 of the top band section 20 are detached from the trunnions 26 of the band section 24 and are applied to the trunnions 26 of the band section

23. The trunk section 12 is removed and the top band section 20 is swung in the center groove 15 of the trunk section 11. The lock hasp 29 is swung to a position to engage 5 the lock section 30 with the lock section 31 of the band section 23, thus securing the trunk sections 10 and 11 to each other. When in locked position the top and bottom band sections 20 and 21 are disposed within 10 the top and bottom center grooves 15 and 16 respectively to prevent lateral movement of the band from the trunk sections. The band will function to retain the ribs 17 and grooves 18 whereby to prevent lateral relative movement between the trunk sections and will prevent longitudinal or horizontal 15 relative movement thereof, thus effectively retaining the sections against separation.

It is to be understood that the right is 20 reserved to embodiments other than those actually illustrated herein, to the full extent indicated by the general meaning of the terms in which the claims are expressed or by variations in the phraseology of the 25 same.

Having thus described my invention, I claim as new and desire to secure by Letters Patent:

1. The combination with a trunk including a plurality of separable trunk sections, 30 each provided with spaced ribs on the bot-

tom walls and spaced grooves in the top walls inter-engageable with the other trunk sections to prevent lateral separation thereof when assembled, said trunk sections having centrally arranged grooves in the top and bottom walls thereof, of a band adapted to embrace said trunk sections for retaining the same against separation. 35

2. The combination with a trunk including a plurality of separable trunk sections, each provided with spaced ribs on the bottom walls and spaced grooves in the top walls adapted for interchangeable inter-engagement with the other trunk sections to prevent lateral separation thereof when assembled, said trunk sections having centrally arranged grooves in the top and bottom walls thereof, of a band adapted to embrace said trunk sections for retaining the same against separation, said band including common top and bottom sections and a plurality of side sections each corresponding in height to its respective broken section, inter-engageable means on the opposite extremities of each band section, a common locking means carried by the top band section, a second locking means carried by each of the band sections of the side, adapted to coact with the common locking means to 50 retain the band sections against separation. 55

DAVID B. HART.
